UNITED STATES PATENT OFFICE.

GEORGE A. WIELAND, OF DULUTH, MINNESOTA, ASSIGNOR TO SYLVESTER GEORGE STEVENS, OF DULUTH, MINNESOTA.

DERRICK FOR PULLING STUMPS.

1,096,337.

Specification of Letters Patent. Patented May 12, 1914.

Application filed May 21, 1912. Serial No. 698,810.

To all whom it may concern:

Be it known that I, GEORGE A. WIELAND, a citizen of the United States, residing at Duluth, in the county of St. Louis and State 5 of Minnesota, have invented certain new and useful Improvements in Derricks for Pulling Stumps, of which the following is a specification, reference being had therein to the accompanying drawing.

10 My invention relates to improvements in derricks for pulling stumps.

The object of my invention is to provide a derrick of this character which is mounted on a movable support, which can be readily 15 transported from place to place and at the same time providing a derrick in which the boom is relieved of a great amount of strain and at the same time providing means whereby the supports for the outer end of 20 the boom may adjust themselves when using the derrick on uneven ground.

Another object of my invention is to provide a simple, cheap and effective derrick of this character having certain details of 25 structure hereinafter fully set forth.

In the accompanying drawings—Figure 1 is a side elevation of my improved derrick in the act of pulling a stump. Fig. 2 is a vertical cross-sectional view of the supporting means for the outer end of the boom and showing the oscillating connection with the same.

Referring now to the drawings, 1 represents a movable frame, or skid, upon which 35 is mounted the hoisting machinery 2. While I have shown this supporting means or frame in the form of a skid, it will be understood that it can be mounted on a vehicle if desired. The forward end of the 40 frame or skid 1 is provided with a mast 3. Carried by the lower end of the mast 3 is a boom 4. This boom has a universal connection with the mast, whereby the boom may be raised or lowered or may be swung in any 45 direction whereby the outer end thereof may be brought directly over the stump.

Secured to the outer end of the boom 4 is a cable 12, which passes inwardly over a block 13, carried by the upper end of the 50 mast 3, and said cable extends downwardly and is operated by the hoisting machinery 2. Surrounding the outer end of the boom 4, on the inside of the connection with the cable 12, is an elongated sleeve 5. This 55 sleeve is adapted to oscillate upon the boom

but held against longitudinal movement thereon. The said sleeve on opposite sides is provided with eyes 5', which are adapted to interlock with the eyes 6' and 7' carried by sleeves 8 and 9 rigidly secured on the legs 60 6 and 7.

The legs 6 and 7 are of an elongated form, as clearly shown in Fig. 1, of the drawings, and have their lower ends provided with foot pieces 10, which are pivotally connected thereto. This pivotal connection of the foot pieces allows the foot piece to adjust 65 itself to the ground as will be readily understood. The upper ends of the legs 6 and 7 extend above the boom 4, as is also clearly 70 shown in Fig. 1, of the drawings.

Secured to the upper ends of the legs 6 and 7 are separate cables 8' and 9', which extend inwardly over a block 14, carried by the mast adjacent its base, and said cables 75 leading to the hoisting machinery 2. Secured to the legs 6 and 7 below the boom are the cables 10 and 11, which extend horizontally and pass over a block 15 carried by the boom. The said cables extend inwardly and 80 pass over the block carried by the lower end of the mast and are also operated by the machinery 2. While I have described these cables 8', 9', 10 and 11 as being operated by the hoisting machinery 2, it will be understood 85 that the same can be operated by hand without departing from my invention.

The sleeve 5 is provided with an eye 16, in which is hooked the hook 17 carrying the block 18. Passing around the block 18 is a 90 cable 19, which extends along the lower face of the boom and passes to the hoisting machinery 2 and is operated thereby. The said cable also passes around the block 20 carrying a hook 21, which is adapted to 95 hook into the chain 22, which is fastened around the stump and forms the hoisting or pulling means for the stump.

In operation it will be seen that the skid or frame 1 is placed adjacent the stump to 100 be removed. The boom 4 is then swung around in a position so that its outer end is in a vertical alinement over the stump. The cables 8', 9', 10 and 11 are then operated so that the legs 6 and 7 are on opposite sides 105 of the stump. The oscillating sleeve 5 carried by the boom allows one leg to move upwardly and the other downwardly should the ground on one side of the stump be higher than that of the other, whereby the 110

boom is evenly supported from both sides of the stump. The chain 22 is then fastened around the stump and the hook 21 of the block 20 is connected to the chain. The 5 cable 19 is then operated by the hoisting machinery 2 and the stump is drawn upwardly.

By the structure herein shown and described, it will be seen that the boom 4 and 10 mast 3 may be made of much lighter material and yet have a great lifting strength, as the legs 6 and 7 support the outer end of the boom. The legs 6 and 7 also prevent the pulling action on the cable 14 from tilting 15 the skid or frame 1 by the pull on the stump.

Having thus described my invention what I claim and desire to secure by Letters Patent is:

1. A derrick comprising a frame, hoisting 20 machinery carried by the frame, a boom pivotally mounted upon the frame, legs independently pivotally mounted upon the outer end of the boom and having an oscillating movement on the boom independent of their 25 pivotal connection and means intermediate the legs for pulling a stump.

2. A derrick comprising a portable frame, hoisting machinery carried by the frame, a boom pivotally mounted upon the frame, 30 legs independently pivotally carried by the boom and having an oscillating movement thereon independent of their pivotal connection, means for adjusting said legs and means connected to the boom for pulling a 35 stump.

3. A derrick comprising a frame, hoisting machinery carried by the frame, a boom pivotally mounted upon the frame, legs intermediate pivotally mounted to the boom adjacent its 40 outer end, means connected to the legs above and below the boom for adjusting the same, and means carried by the boom intermediate the legs for hoisting or pulling the stump.

4. A derrick comprising a frame, hoisting 45 machinery carried by the frame, a boom pivotally mounted upon the frame, means operated by the machinery for adjusting said boom, legs independently supported and having an oscillating connection with the boom adjacent its outer end, means for adjusting said legs, and means carried by the boom intermediate the legs for hoisting or pulling a stump.

5. A derrick comprising a frame, hoisting 55 means carried by the frame, a boom pivotally mounted upon the frame, means carried by the frame for operating the boom, an oscillating sleeve carried by the outer end of the boom, legs loosely connected to said 60 sleeve, means for adjusting said legs, and means carried by the boom intermediate the legs for hoisting or pulling a stump.

6. A derrick comprising a portable frame, hoisting machinery carried by the frame, a 65 boom pivotally mounted upon the frame,

means carried by the frame for adjusting said boom, an oscillating sleeve mounted upon the outer end of the boom, two legs loosely connected to said sleeve intermediate their ends, cables operated from the frame 70 and connected to the legs below the boom, cables operated from the frame and connected to the legs above the boom, a block and tackle supported by the sleeve between the legs and operated by the hoisting machinery. 75

7. A derrick comprising a portable frame, a mast carried by the frame, hoisting machinery carried by the frame, a boom pivotally carried by the mast adjacent its lower end, a cable operated by the hoisting machinery and extending over a block carried by the upper end of the mast and secured to the outer end of the boom, an oscillating sleeve carried by the outer end of the boom 80 and having eyes on opposite sides, legs on opposite sides of the boom and having eyes below their upper ends and interlocking with the eyes carried by the sleeve, cables secured to the upper end of the legs and operated by the hoisting machinery, cables 85 secured to the legs below the eyes and operated by the hoisting machinery, an eye carried by the lower face of the sleeve, a block and tackle supported in the said eye, 90 means carried by the lower end of the block and tackle for connecting it with a stump, said block and tackle having its cable extending inwardly and operated by the hoisting machinery and pivoted feet carried by 100 the lower end of the legs.

8. A derrick comprising a frame, a hoisting mechanism carried thereby, a boom mounted upon the frame, legs independently pivotally mounted upon the outer end of the 105 boom and having an oscillating movement thereon, and means for adjusting its legs and means connected to the boom intermediate the legs for pulling a stump.

9. A derrick comprising a frame, a hoisting mechanism carried thereby, a boom mounted upon the frame, legs independently pivotally mounted upon the outer end of the boom and having an oscillating movement thereon, means for adjusting said legs and 115 means connected to the boom intermediate the legs for pulling the stump.

10. A derrick comprising a frame, a hoisting mechanism carried by the frame, a boom pivotally mounted upon the frame, 120 legs independently pivotally mounted upon the outer end of the boom and having an oscillating movement thereon, means for adjusting said legs, and a hoisting cable connected to the boom intermediate the legs. 125

11. A derrick comprising a frame, a hoisting mechanism carried by the frame, a boom pivotally mounted upon the frame, legs flexibly connected to the boom adjacent its outer end, two independent cables con- 130

nected to each leg above and below the boom for adjusting the same, and a hoisting cable carried by the boom intermediate the legs, substantially as shown and described.

5 12. A derrick comprising a frame, hoisting machinery carried by the frame, a boom pivotally mounted upon the frame, means carried by the frame for operating the boom, an oscillating member carried by the outer
10 end of the boom, legs independently loosely

connected to said member, means for adjusting said legs and means carried by the boom intermediate the legs for hoisting or pulling a stump.

In testimony whereof I hereunto affix my 15
signature in the presence of two witnesses.

GEORGE A. WIELAND.
